DISPLAY RACK FOR CARPET SAMPLES OR THE LIKE

James L. Chenot, Louisville, Ohio, assignor to The R & J
Furniture Company, Canton, Ohio, a corporation of Ohio

Filed Oct. 12, 1961, Ser. No. 67,057

Term of patent 14 years

(Cl. D80—9)

Fig. 1

Fig. 2

FIG. 1 is a front perspective view taken from one side of a display rack for carpet samples or the like embodying my new design; and

FIG. 2 is a side elevational view thereof.

It should be understood that the wire mesh, fragmentarily shown, is continued throughout the areas indicated.

I claim:

The ornamental design for a display rack for carpet samples or the like, as shown and described,
